Primary Examiner—Brian N. Vinson*Attorney, Agent, or Firm*—Cushman Darby & Cushman IP
Group of Pillsbury Madison & Sutro, LLP[57] **CLAIM**

The ornamental design for a folding handle for a sleigh shovel, as shown and described.

DESCRIPTION

FIG. 1 is a top, front, and left side perspective view of folding handle for a sleigh shovel showing our new design; FIG. 2 is a left side elevational view thereof; FIG. 3 is a right side elevational view thereof; FIG. 4 is a front elevational view thereof; FIG. 5 is a rear elevational view thereof; FIG. 6 is a top plan view thereof; FIG. 7 is a bottom plan view thereof; FIG. 8 is a top, front, and left side perspective view thereof, shown in a folded position; FIG. 9 is a left side elevational view thereof, shown in a folded position; FIG. 10 is right side elevational view thereof, shown in a folded position; FIG. 11 is a front elevational view thereof, shown in a folded position; FIG. 12 is a rear elevational view thereof, shown in a folded position; FIG. 13 is a top plan view thereof, shown in a folded position; and, FIG. 14 is a bottom plan view thereof, shown in a folded position. The broken-line disclosure of a shovel blade in the views is for illustrative purposes only and forms no part of the claimed design.
